ABSTRACT OF THE DISCLOSURE

Bridged dinuclear transition metal compounds are prepared by the reaction of a first transition metal compound having two non-chelating ligands containing electron-donating groups, in *cis* positions relative to each other, with a second transition metal compound containing two displaceable ligands also in *cis* positions relative to each other, so that a bridged dinuclear product is formed with the elimination of the displaceable ligands.

This invention relates to a process for preparing bridged dinuclear transition metal compounds, in which the metal atoms may be the same or different.

According to the present invention a first transition metal compound having two non-chelating ligands containing electron-donating groups in *cis* positions relative to each other, is reacted with a second transition metal compound containing two displacable ligands also in *cis* positions relative to each other, so that a bridged dinuclear product is formed with elimination of the displacable ligands.

The transition metals of Groups IV-A to VIII and I-B of the Periodic Table may be incorporated in compounds produced by the process of our invention. Examples of suitable transition metals include titanium, molybdenum, cobalt, rhodium and ruthenium, platinum, palladium and nickel.

The term "displaceable ligand" refers to any ligand bonded to the second transition metal compound which is displaced in the course of the reaction by the electron-donating atoms of the ligands of the first transition metal compound. Typically these are neutral ligands such as hydrocarbon ligands like norbornadiene or ethylene. Phenyl cyanide is also readily displaceable. Alternatively they may be co-ordinated solvent molecules, such as ethers, for example 2-methoxyethanol. It should be noted that a single ligand of the norbornadiene type leaves the second transition metal compound to form both of the necessary co-ordination sites.

The term "electron-donating group" is used to include groups comprising atoms of elements of Groups V-B, VI-B and VII-B of the Periodic Table of Elements, especially, sulphur, the halides, and unsaturated hydrocarbon groups, such as acetylenic groups.

The process of the invention is exemplified formally by the following general equation, which has no steric significance other than illustrating the *cis* relationship of the reacting ligands

2

In the above equation M and M' represent transition metal atoms, which may be the same or different. The first transition metal compound containing metal M also contains two non-chelating ligands X—Rn (wherein X represents an electron donor atom, R represents substituents and n is an integer, being 2 when X is a Group V-B element, 1 when X is a group VI-B elements and 0 when X is a Group VII-B element). It also contains mother ligands L which satisfy the co-ordination requirements of metal M. The second transition metal compound contains displaceable ligands L', (or a single divalent ligand such as norbornadiene) and p further ligands L''. In the course of the reaction, ligands L' are displaced to give a single bridged compound as the product.

The process is conveniently carried out in a solvent which may be inert or capable of liganding with the second transition metal compound to form displaceable ligands. Examples of suitable solvents are toluene, methylene chloride or 2-methoxyethanol. The reaction usually occurs at room temperature and pressure though higher or lower temperatures and pressures may be used if desired. The product often precipitates out of solution, though recovery may be aided by evaporation of the solvent and/or addition of a precipitating agent such as an aliphatic hydrocarbon. The products may be purified by recrystallisation or by chromatography. Since the starting materials and products are often air and water sensitive, reaction should be carried out under dry, inert atmosphere, for example, nitrogen.

The products of the process of my invention are useful as catalysts in a wide range of organic reactions. For example, compounds containing ruthenium may be used as hydrogenation catalysts; compounds containing platinum may be used as hydrosilation catalysts.

The invention will now be illustrated by the following examples in which parts are by weight.

All reactions were carried out under nitrogen.

EXAMPLE 1

Dicyclopentadienylthiophenyltitanium (20 parts) and norbornadienetracarbonylmolybdenum (15 parts) were dissolved together in toluene (430 parts) and the solution was stirred for 24 hours at room temperature. The purple colour of the starting material was retained but a deep blue solid was deposited. This compound is soluble in methylene chloride (from which it is reprecipitated by methylcyclohexane), chloroform, tetrahydrofuran, acetone and sparingly so in benzene. It does not decompose below 230° C. The infrared spectrum shows the presence of cyclopentadienyl, thiophenyl and carbonyl functions.

Elemental analysis.—(Calculated figures in brackets), percent: C, 51.1 (51.6); H, 3.2 (3.3); S, 11.2 (10.6).

Analytical data is consistent with the structure:

where Cpd=cyclopentadienyl and Ph=phenyl.

3
EXAMPLE 2

Bis(ethylene)rhodium (I) acetylacetonate (57 parts) was dissolved in toluene (1800 parts) and bis(triphenylphosphine) cobalt (II) chloride (144 parts) was added. Within an hour at room temperature the blue solution became yellow and after a further two hours a yellow solid (182 parts) was filtered off. Melting point: 150–153° C. Infra red spectra showed the presence of triphenylphosphine and acetylacetone ligands.

Elemental analysis.—C, 57.3 (57.5); H, 3.8 (4.4); Cl, 8.1 (8.3); P, 7.3 (7.3); Co, 7.1 (6.6).

Analytical data is consistent with the structure:

where acac=acetylacetone and Ph=phenyl.

EXAMPLE 3

Bis(ethylene) rhodium (I) acetylacetonate (10 parts) was dissolved in toluene (350 parts) and bis(triphenylphosphine) nickel dichloride (24 parts) was added. After stirring for 2 hours at room temperature, a yellow precipitate (321 parts) was filtered off, washed with pentane and dried. Melting point: 140–142° C.

Elemental analysis.—C, 57.8 (57.3); H, 4.8 (4.4); Cl, 7.3 (8.2).

Analytical data is consistent with the structure:

EXAMPLE 4

Bis(phenyl cyanide) palladium dichloride (10 parts) and bis(triphenylphosphine) cobalt dichloride (17 parts) were dissolved in methylene chloride (650 parts) and the solution was stirred for 15 hours. A pale yellow powder (28 parts) was precipitated and was filtered off, washed with methylene chloride and dried. Melting point 235–237° C. with decomposition.

Elemental analysis.—C, 50.1 (52.0); H, 3.7 (3.6); Cl, 17.0 (17.5); Pd, 12.8 (12.8); Co, 9.3 (7.0).

Analytical data is consistent with the structure:

EXAMPLE 5

Bis(phenyl cyanide) platinum dichloride (10 parts) and bis(triphenylphosphine) cobalt dichloride (14 parts) were dissolved in methylene chloride (600 parts). After two hours, a white precipitate (20 parts) formed which was filtered off, washed with methylene chloride and dried. Melting point: >250° C.

Elemental analysis.—C, 45.5 (46.0); H, 3.4 (3.2); Cl, 14.9 (15.3); Pt, 15.5 (21.0); Co, 5.1 (6.4).

Analytical data is consistent with the structure:

EXAMPLE 6

Bis(phenyl cyanide)palladium dichloride (10 parts) and bis(triphenylphosphine) nickel dichloride (15 parts) were dissolved in methylene chloride (900 parts). A yellow precipitate immediately formed and all trace of the nickel complex disappeared. The mixture was stirred for an hour to complete the reaction and the product (17 parts) was then filtered off and dried. Melting point: >250° C.

Elemental analysis.—C, 50.2 (52); H, 3.9 (3.6); Cl, 17.2 (17.0); Pd, 10.5 (13.4); Ni, 7.6 (7.0).

4

Analytical data is consistent with the structure:

EXAMPLE 7

Bis(phenyl cyanide) palladium dichloride (10 parts) and dicyclopentadienyldithiophenyltitanium (11 parts) were dissolved in toluene (500 parts) and stirred for an hour, after which a red precipitate formed. After a further half hour the product (II parts) was filtered off and dried. Melting point: >250° C.

Elemental analysis.—C, 46.0 (46.2); H, 3.3 (3.5); Cl, 10.2 (12.4); Ti, 9.1 (8.5); Pd, 20.2 (18.5).

Analytical data is consistent with the structure:

EXAMPLE 8

Bis(diphenylphosphino)ethanedi thiophenylnickel (18 parts) and bis(ethylene) rhodium acetylacetonate (5 parts) were dissolved in toluene. After two hours a precipitate (13 parts) was filtered off and dried. Melting point: 265° C.

Elemental analysis.—C, 59.3 (58.9); H, 4.2 (4.9).

Analytical data is consistent with the structure:

EXAMPLE 9

Bis(diphenylphosphino) ethanepalladium dichloride (16 parts) and bis(phenyl cyanide) palladium dichloride (22 parts) were dissolved in toluene and left to stand for 46 hours. At the end of this time the product (19 parts) was filtered off, and dried it did not decompose below 300° C.

Elemental analysis.—C, 41.7 (41.5); H, 3.2 (3.2).

Analytical data is consistent with the structure:

What I claim is:

1. A process for the preparation of bridged dinuclear transition metal compounds which comprises the reaction of

(a) a first transition metal compound having directly bonded to the metal two non-chelating ligands containing electron-donating groups in *cis* positions relative to each other, the compound also including other ligands as required to satisfy the valence and co-ordination requirements of the metal, said compound (a) being represented by the formula:

with

(b) a second transition metal compound containing a displaceable norbornadiene ligand or two other displaceable ligands in *cis* position relative to each other, said second compound (b) being represented by the formula:

the reaction causing the displaceable ligands to be 10 displaced from the second transition metal compound so as to form a bridged dinuclear compound represented by the formula:

wherein L is cyclopentadienyl, triphenylphosphine and diphenylphosphinoethane, m is 2, M is the first transition metal, X is sulphur, acetylene or chlorine, n being 0 when X is acetylene or chlorine and n being 1 and R being phenyl when X is sulphur, L' being ethylene, phenyl cyanide, 2-methoxyethanol or both L' taken together being norbornadiene, M' is the second transition metal, L'' is carbonyl, acetylacetone and chlorine and p is 1 or 2, being sufficient to satisfy the requirements of the second metal M'.

2. A process according to claim 1 in which the reaction is carried out in a solvent capable of liganding with the second transition metal compound to form displaceable

ligands, said solvent being selected from the group consisting of toluene, methylene chloride and 2-methoxyethanol.

3. A process according to claim 1 in which the metal 5 is selected from rhodium, cobalt, nickel, palladium, platinum, molybdenum and titanium.

4. A process according to claim 1 wherein the first transition metal compound (a) is selected from the group consisting of dicyclopentadienyldithiophenyltitanium, bis (triphenylphosphine) cobalt dichloride, bis (triphenylphosphine) nickel dichloride, bis (diphenylphosphino)ethane-dithiophenylnickel, and bis (diphenylphosphino)ethane-palladium dichloride, and wherein

the second transition metal compound (b) is selected 15 from the group consisting of norbornadienetetracarbonylmolybdenum, bis (ethylene) rhodium acetylacetone, bis (phenyl cyanide) palladium dichloride, and bis (phenyl cyanide) platinum dichloride.
